ELECTRIC SWITCH

Ralph S. Bennett, Pittsfield, Mass., assignor to
General Electric Company, a corporation of
New York

Application October 6, 1933, Serial No. 692,469

8 Claims. (Cl. 200—114)

My invention relates to electric switches and more particularly to switches combined with fuses which are adapted to open upon operation of the fuse.

5 In the protection of overhead outdoor transmission lines it has become a common practice to combine a fuse with the line switch. For economy and safety, it is desirable to locate the switch and the fuse combined with it near the 10 top of the pole adjacent the transmission line. The opening and closing of the switch may be accomplished by a long switch stick with a hook adapted to engage the switch handle. However, examination of the fuse to determine whether 15 or not it has operated and replacement of the fusible element is hazardous due to the close proximity of the live switch contact and transmission line. Combined switches and fuses have been provided with an arrangement for automatically opening the switch when the fuse operates. In this manner the operation of the fuse is clearly indicated without the necessity of a close examination. The automatic opening of the switch has the additional advantage of removing 20 the voltage stress from the fuse holder after the operation of the fuse. While the fuse is intact there is no voltage stress on the fuse holder. When the fuse has completed its operation before the switch begins to open no arc is drawn 25 between the switch and contact. On the other hand, if the switch does begin to open before the fuse has completed its operation, an arc may be drawn between the switch and contact which would do serious damage to the fuse holder and 30 may require its replacement.

An object of my invention is to provide an improved switch and combined fuse of rugged construction, easy to assemble and mount in position, and of relatively low cost of manufacture. 40 What I consider to be novel and my invention will be better understood by reference to the following specification and appended claims when considered in connection with the accompanying drawing, in which Fig. 1 is a perspective view of the combined switch and fuse of my invention; Fig. 2 is an exploded view in perspective on an enlarged scale of a combined clamp and connector; Fig. 3 is an enlarged view in section of the combined clamp and connector in position; 45 and Fig. 4 is an enlarged sectional view of the fuse holder and contact cap.

50 Referring to the drawing, 10 indicates a cross arm secured to a pole, not shown, on which the transmission lines are carried. An insulator 11 is mounted on the cross arm by means of a strap

12 and a two-part clamp 13. Strap 12 consists of a flat strip of metal surrounding a central portion 14 of insulator 11 of reduced diameter. Strap 12 is held in close engagement with central portion 14 by means of a bolt 15. Strap 12 is secured to one part of two-part clamp 13. The two parts of clamp 13 are secured in engagement with opposite sides of cross arm 10, which may vary in thickness, by means of bolts 16. A metal rod 17 which may consist of copper forms a switch contact 18 and extends around the upper end of insulator 11 seating in an annular groove 19. The arrangement of the metal rod 17 to form the switch contact 18 and supporting it in an annular groove 19 greatly simplifies the assembly 15 and reduces the cost of manufacture of the switch as compared with one supported on inserts cemented in an opening in the insulator. The two free ends of rod 17 are flared outwardly adjacent switch contact 18 and form a V between them 20 to guide a movable switch contact to contact 18. To secure rod 17 in firm engagement with insulator 11 and also to provide an electrical connection for switch contact 18 a combined clamp and connector 20 is provided. Referring to Fig. 25 2, it may be seen that combined clamp and connector 20 consists of two identical parts 21 and 22 which are provided with semi-circular transverse grooves 23 and 24 respectively in which the two parts of rod 17 are adapted to be clamped. 30 The semi-circular shape of these grooves 23 and 24 provides surfaces which closely engage the rod 17 and clamp it tightly without any danger of severing the rod upon the tightening of the clamp. To guide rod 17 into grooves 23 and 24, 35 longitudinal projections 25, 26, and 27 from part 21 and projections 28, 29, and 30 from part 22 are provided. Each of these projections have an inclined surface adjacent grooves 23 and 24 to gradually force the rod 17 toward the center 40 into the grooves 23 and 24 as parts 21 and 22 are drawn together. Projection 25 of part 21 passes between projections 29 and 30 of part 22, and projection 28 of part 22 passes between projections 26 and 27 of part 21 as the two parts 45 are drawn together. To draw parts 21 and 22 together, a stud 31 is provided which passes through part 22 and threads into part 21. The head 32 of stud 31 engages the bottom surface of part 22 and draws part 21 tightly down against 50 part 22 as it is threaded through the central opening 33 of part 21. To provide for the electrical connection of a conductor 34 connected to one of the overhead transmission lines to rod 17 and switch contact 18, a longitudinal slot 35 is pro- 55

vided in stud 31. The bared end of conductor 34 is laid in the slot 35. To hold the bared end of conductor 34 in slot 35, a nut 36 is provided with a metal clip 37 which is adapted to slide in slot 35. Clip 37 is of substantially the width of slot 35 and is provided with a lower flat contact surface 38 and two integral arcuate projections 39 and 40 which are adapted to pass through the opening of nut 36 and engage the opposite face 10 to hold the clip 37 loosely in the nut 36. By this arrangement, a large contact area is provided for engagement with the bared end of conductor 34 and the conductor is clamped between two surfaces which do not have any tendency to sever 15 the conductor 34. By the provision of combined clamp and connector 20 the switch contact 18 is held securely in position on insulator 11 and the electrical connection for the switch contact is provided with a minimum number of operations 20 to mount the switch contact and make the electrical connection to rod 17. Secured to the lower end of insulator 11 is a rod 41 which seats in an annular groove 42. Rod 41 is held in position in groove 42 by means of a combined clamp 25 and connector 43 which is identical to the combined clamp and connector 20. The free ends of rod 41 are turned inwardly toward each other and pass into a cylindrical bushing 44 which provides a pivot for switch 45. A fuse holder 46 30 consisting of a tube of insulating material carries a fuse link 47 within its central bore extending from the lower open end of fuse holder 46. A cap 48 closes the upper end of fuse holder 46 and holds fuse link 47 in engagement with 35 the top of fuse holder 46. As better indicated in Fig. 4, fuse link 47 has a contact button 49 which rests on the top of fuse holder tube 46. Contact cap 48 is threaded directly on the fuse holder tube 46. Between contact button 49 and contact cap 48 a spiral spring 50 is located which serves to 40 provide sufficient pressure to hold contact button 49 in engagement with the top of tube 46 despite a variation in the space provided in cap 48 to allow for the relatively large expansion and contraction of the insulating material of tube 46 as compared to the metallic contact cap 48. Spring 50 also serves to provide a good electrical connection between cap 48 and contact button 49 regardless of the expansion or contraction of tube 46. Cap 48 is provided with a conical projection 51 which is adapted to engage switch contact 18. Due to the shape of projection 51, upon automatic 45 opening of the switch on operation of the fuse, rotation of fuse holder 46 is prevented and opening of the switch retarded to permit the extinction of the arc within fuse holder 46 before the beginning of the opening of switch 45. This arrangement is important because if switch 45 should open before the arc is extinguished within 50 fuse holder 46, a secondary arc may be drawn between the cap 48 and switch contact 18 which would be more difficult to extinguish than an arc drawn within the fuse holder 46 and in addition may do serious damage to the fuse holder and support and require its subsequent replacement. For the manual opening of switch 45 and its removal for replacement after operation of the 55 fuse, operating handle 52 is provided and secured on fuse holder 46 adjacent to cap 48. To prevent radio interference by a static electric discharge between operating handle 52 and cap 48, a copper wire spring 53 is provided engaging operating handle 52 and contacting with cap 48. Operating handle 52 is so formed as to permit 60 the manual opening of the switch by the engage-

ment of the usual hook provided on a switch stick and also for removal of the switch 45 by the same switch stick. The operating handle 52 and cap 48 with its conical projection are not my invention, but are the subject of another application Serial No. 692,414 filed concurrently herewith in the name of B. R. Hermann and assigned to the same assignee to which this application is assigned.

Fuse holder 46 is carried on rod 41 by a fuse holder support 54 and toggle 55. Toggle 55 is pivotally connected to fuse holder support 54 by means of a pivot pin 56. Toggle 55 is pivotally supported on bushing 44. To prevent lateral movement of toggle 55, side plates 57 and 58 15 are provided and secured to rod 41 on the adjacent ends of bushing 44. Fuse link 47 is connected to toggle 55 by means of a thumb screw 59. As long as the fuse is intact, toggle 55 is held in the position indicated in Fig. 1 with a projection 60 20 in engagement with fuse holder support 54. Upon operation of the fuse, toggle 55 is released and rotates about bushing 44. Fuse holder 46 does not immediately follow the movement of toggle 55. Initially fuse holder 46 moves longitudinally 25 until projection 51 is freed from engagement with switch contact 18 and then it rotates about pivot pin 56 until fuse holder support 54 is in engagement with projection 60 of toggle 55. The fuse holder tube 46 may then be removed from the 30 lower contact 41 and fuse link 47 renewed. Fuse holder 46 may then be replaced and the circuit completed in the usual manner by closing switch 45.

From the foregoing it will be seen that a com- 35 bined fuse and switch is provided of rugged construction which is easy to assemble and mount in position and is of relatively low cost of manufacture.

What I claim as new and desire to secure by 40 Letters Patent of the United States, is:

1. An electric switch comprising an insulator, a rod surrounding one end of said insulator and forming a contact surface near its free end, a second rod surrounding the other end of said insulator, clamps to secure said rods to said insulator, a fuse holder, means to support and pivot the fuse holder on said second-mentioned rod, a contact secured to said fuse holder and adapted to engage said first-mentioned rod, and means to 50 connect conductors to each of said rods.

2. An electric switch comprising an insulator, means to support said insulator, a stationary switch contact formed of a rod extending about the end of said insulator, a clamp to secure said contact to said insulator, a second switch contact formed of a rod surrounding the other end of said insulator, a clamp to secure said second contact to said insulator, a fuse holder, means to support and pivot said fuse holder on said 60 second-mentioned contact, a contact secured to said fuse holder and adapted to engage said first-mentioned contact, means to connect a conductor to said clamp securing the first-mentioned contact to the insulator, and means to connect a 65 conductor to said clamp securing the second-mentioned contact to the insulator.

3. In an electric switch, an insulator, a stationary switch contact consisting of a rod passing around one end of said insulator and seated 70 in an annular groove, a two-part clamp engaging said rod, a stud passing through said clamp to secure said clamp in close engagement with said rod, and a nut adapted to secure a conductor in a longitudinal slot in said stud. 75

4. A combined clamp and connector comprising a two-part clamp having interengaging parts and a transverse groove, a stud for securing said two-part clamp together with a rod seated in said transverse groove, said stud having a longitudinal slot, and a nut threaded on said stud and adapted to secure a conductor in the slot.

5. A combined clamp and connector comprising a part having a transverse groove and longitudinal projections, a second part having a transverse groove adapted to register with the transverse groove in said first-mentioned part and having projections nesting with the projections in said first-mentioned part, a stud 10 passing through said clamping portions for securing them together to clamp a rod in said transverse grooves and having a longitudinal slot, and a nut having a contact clip adapted to slide in the slot of said stud and engage a conductor to secure it in the slot when the nut is threaded on the end of the stud.

6. A combined connector and clamp adapted to secure a rod in an annular groove in an insulator comprising a clamp having transverse 20 grooves and projections with surfaces extending angularly from said grooves, a stud for securing said clamp on a rod which rod is guided to said grooves by said projections and adapted to be seated in said grooves by the tightening of the clamp, said stud having a longi-

tudinal slot, a nut arranged to engage said stud and a contact clip secured to said nut and adapted to slide in the slot in said stud and secure a conductor in the slot when the nut is threaded on the end of the stud.

7. An electric switch comprising an insulator, a supporting strap passing around a reduced portion of said insulator, a metal rod secured in an annular groove in one end of said insulator, a second metal rod secured in an annular groove in the other end of said insulator, a fuse holder, a contact secured to said fuse holder and adapted to engage said first-mentioned rod, means to pivotally support said fuse holder on said second-mentioned rod, and means to connect a conductor to each of said rods.

8. An electric switch and support comprising an insulator, means to support said insulator, a metal rod secured in an annular groove in one end of said insulator, a contact surface formed 20 between abutting ends of said rod, a second metal rod secured in an annular groove in the other end of said insulator, a fuse holder, a contact secured to said fuse holder and adapted to engage said first-mentioned rod, means to pivotally support said fuse holder on said second-mentioned rod, and means to connect a conductor to each of said rods.

RALPH S. BENNETT. 30
